UNITED STATES PATENT OFFICE.

JACOB J. BUSENBENZ, OF CHICAGO, ILLINOIS.

TIME-STAMP.

SPECIFICATION forming part of Letters Patent No. 546,651, dated September 24, 1895.

Application filed September 29, 1894. Serial No. 524,457. (No model.)

To all whom it may concern:

Be it known that I, JACOB J. BUSENBENZ, a citizen of the United States, residing at Chicago, in the county of Cook and State of Illinois, have invented a new and useful Improvement 5 in Time-Stamp, of which the following is a specification.

My invention relates to an improvement in the class of apparatus known as "time-stamps" for affording means adapted to be operated to stamp upon papers, cards, and the like the time, as the exact minute in any hour of a day during the month in a year wherein the stamping operation is performed, and other matter or legend which it is desired to record by causing the mechanism from which the impression is taken to be actuated by a clock-movement to correspond therewith in the time to be recorded, or at 20 least with some of the divisions thereof.

In its main aspect my invention relates to the class of electrically-operated time-stamps, meaning thereby a time-stamp employing an electromagnet periodically energized by including it in circuit with a clock adapted to close the magnet-circuit at predetermined intervals—say, of minutes—to cause the magnet to attract its armature, and thereby release spring or weight actuated mechanism to permit it to advance the media carrying the record-imprinting characters to the point of stamping in accordance with the progress of time as indicated by the clock.

The primary object of my improvement as applied to the class of time-stamps thus outlined is to render it in itself a time-indicator or secondary clock, employing releasing mechanism normally to hold the clock-movement against running by restraining its motor (spring or weight) and by periodically energizing the magnet, causing the consequent attraction of the armature to effect release of the motor and resultant step-by-step advancement of the hands of the time-stamp or secondary clock in accordance with the periodical action of the primary-clock movement in the magnet-circuit, and to employ the secondary-clock movement as the motor for moving in correspondence with its progress the 45 printing-ring or calendar or any desired number thereof carrying the characters to be imprinted by stamping.

My further object in this connection is to avoid any connection between the calendar advancing means and the actuating mechanism therefor, operated by the motor of the time-stamp or secondary-clock movement, when released by the working of the electromagnet that would cause the secondary-clock movement to be affected as to stoppage or by 60 impediment or any form of interference with its time-keeping function by the jar or impact incidental to the stamping blow.

In other particulars my invention relates to improvement in details of construction in a 65 time-stamp, whether of the electrically-controlled variety herein referred to or to other varieties of time-stamps, including the principle of construction set forth in Letters Patent of the United States No. 526,854, dated October 2, 1894, my objects being in the main to provide a simplified set and lock device for the clock-movement and calendar or printing-ring mechanism more immediately actuated thereby; also to enable independent key-setting of the hour-hand of the clock on the time-stamp, more particularly of the hour-printing wheel and also of the date-printing wheel, and also to provide an especially-desirable construction of the legend-calendar and of 80 the calendar-detent mechanism.

Referring to the accompanying drawings, Figure 1 represents my improved time-stamp by a view in sectional side elevation, the section being taken at the lines 1 on Figs. 2 and 85 3 and viewed in the direction of the arrow. Fig. 2 is a broken section taken at the line 2 on Fig. 1 and viewed in the direction of the arrow, showing in side elevation the movement of the secondary clock in the time-stamp 90 and its connection with the minute-calendar. Fig. 3 is a view similar to that presented by Fig. 2, except that no calendar is shown, being a section taken at the line 3 on Fig. 1 and viewed in the direction of the arrow. Fig. 4 95 is a broken section taken at the line 4 on Fig. 1 and viewed in the direction of the arrow. Fig. 5 is a broken section taken at the line 5 on Fig. 1 and viewed in the direction of the arrow. Fig. 6 is a broken view showing the 100 calendar-detent mechanism. Fig. 7 is a section taken at the line 77 on Fig. 1 and viewed in the direction of the arrow, and representing, diagrammatically, the electric connection

of the time-stamp controlling-magnet with a primary clock. Fig. 8 is a broken section taken at the line 8 on Fig. 7 and viewed in the direction of the arrow. Fig. 9 is a similar view taken at the line 9 on Fig. 8 and viewed in the direction of the arrow. Fig. 10 is a section taken at the line 10 on Fig. 7, viewed in the direction of the arrow and enlarged, showing the set and lock means I have provided for the calendars and their clock-movement actuating means. Fig. 11 is a plan view of the printing-rings or calendars. Fig. 12 is an inverted view of the printing-rings or calendars. Fig. 13 is a section taken at the line 13 on Fig. 1 and viewed in the direction of the arrow.

General characteristics of the construction of time-stamp forming the subject of the present application will be found in the time-stamp set forth in my aforesaid patent issued on the 2d day of October, 1891—that is to say, it involves rotary printing-rings or calendars, each carrying at suitable intervals apart type indicating divisions of time, the rings being horizontally disposed one within the other, and the spring-controlled train of an ordinary or suitable clock is periodically released to drive the rotary printing-rings or certain of them in accordance with the time indicated on the dial of the timepiece in the time-stamp. A broad difference, however, consists in the fact that in the present construction a single clock-train in the time-stamp performs the twofold function of a time-keeping train and a printing-train having a common motor, (spring,) while according to my former device referred to the two are separate entities in the time-stamp, the time-keeping train having interposed between it and the printing-train releasing mechanism for the latter actuated periodically to cause it to perform its sole function of driving the printing-rings.

A denotes a case containing clock mechanism, that illustrated herein being mainly the common Seth Thomas movement, of which r and r' are two companion clock-springs on shafts carrying, respectively, the gear-wheels q and q' , meshing with a pinion p on the minute-shaft p' , which carries the minute-hand B' in front of a clock-dial B and the toothed wheel o , geared through a pinion n' , and toothed wheel n on a shaft n^2 , with the release-pinion m to drive the latter with its shaft m' sixty times around to one complete revolution of the gear-wheel o . The minute-shaft p' , which is reduced toward its ends, carries a pinion l , Fig. 1, meshing with a gear wheel l' on a stud l^2 , carrying a pinion l^3 , meshing with a gear-wheel l^4 on a sleeve l^5 , loosely surrounding the forward reduced end of the minute-shaft p' , the ratio of the pinion l to the gear l^4 being as twelve to one. On the minute-shaft p' is also the pinion k , meshing with a gear-wheel k' on a stud k^2 , carrying a pinion k^3 , the stud being mounted in a bracket k^4 . The pinion k^3 meshes with the gear-wheel i

on a shaft i' , mounted in a bracket i^2 , which shaft carries a trip-finger i^3 , the proportion between the wheel o on minute-shaft p' and wheel i on the shaft i' being as one to twenty-four.

C is the release-lever, (see Fig. 8,) pivoted between its ends at α to the rear bearing-plate of the clock-movement and terminating at its upper end in a bifurcation, one prong of which is in the form of a hook-stop s , while the other prong affords at its straight extremity a stop s' for a spur s^2 on the rotary shaft m' of the release-pinion m . By oscillating the lever C it alternately removes the hook-stop s and the stop s' out of the path of the spur s^2 , whereby the latter, when the lever is turned to release the spur from bearing downward upon the stop s' , is turned by the action of the springs r r' till it strikes upward against the hook-stop s , which then arrests further turning of the shaft m' till the lever is turned in the opposite direction to take the hook-stop s out of the path of the spur. Thus by oscillating the lever C the shaft m' and pinion m make a half-rotation with each stroke of the lever.

To effect automatically the oscillation of the lever C , I provide an electromagnet D , having its armature D' extended endwise from the lever below its pivotal point to oscillate with it, whereby each time the magnet is energized it attracts the armature, thus swinging the lever in one direction against the tension of its controlling-spring t , and de-energizing the magnet permits the spring t to retract the lever and swing it in the opposite direction.

In order that the oscillation of the lever C and consequent release of the clock-movement in the case A shall be regular according to certain divisions of time—say, minutes—the magnet D is connected in an electric-generator circuit (see the diagrammatic representation in Fig. 7) with a primary timepiece or clock, the minute-shaft of which is represented at v and carries suitably insulated from it a metallic ratchet-wheel W , against a side of which there bears a brush v' , forming one terminal of the generator (battery) E , the other terminal v^2 being indicated as a spring-contact engaging the peripheral teeth of the ratchet W . Thus each time a tooth of the wheel W (shown as provided with sixty teeth) in its rotation makes and breaks contact with the terminal v^2 the battery-circuit is closed and then opened and the magnet D is energized and de-energized alternately to attract and free its armature and oscillate the lever C to release the clock-movement in the case A , the time indicated by the hands on the dial B of which corresponds with that on the primary clock provided with the ratchet W .

Having described the time-keeping and time-indicating functions of the clock-movement in the case A , it remains to describe the manner in which the progressive action of the

train of clock-gear advances the calendars or printing-rings, the construction and mode of operation of which are very much like those of the printing-rings described in my aforementioned patent. In the top or cover N of the case A, which I form with a circular recess or cavity, as formerly, are confined, concentrically, the rotary printing-rings O, O', O², O³, O⁴, and O⁵, of which the ring O carries type for printing legends, as "Sold," "Charged," "Paid," &c. The ring O' is the month-printing ring and is adjustable by hand. The ring O² is the date-printing ring and has on its under face teeth t to be engaged by a pawl M. The ring O³ is the hour-printing ring, having on its under face teeth t' to be engaged by the pawl L. The ring O⁴ is the minute-printing ring and carries on its under face teeth t², and the innermost ring O⁵ has on its upper face type indicating the year. It will be understood that all these rings have upon their upper faces printing-type, which may be cast therewith. The rings O, O', and O⁵ are not provided with teeth to enable them to be moved intermittently by pawls, such as the pawls L and M; but the rings O' and O⁵ are provided with holes t³, adapted to be engaged by spring-controlled pins t⁴, (see Fig. 1,) extending upward through the plate N. The pins t⁴ are so short that a little effort will permit the rings to be turned to break the engagement of the pins and holes, although the rings will be held in sufficiently-firm position during the ordinary operation of printing. The rings O' and O⁵ are movable by hand, and to that end segmental slots u and u' are provided, respectively, coincident with them in the cover-plate N² and correspond in length with the distance apart of holes t³ in the rings to admit any suitable pins by which to move the ring the distance of a slot.

The outermost ring is cut away in part of its periphery to receive a spring t⁶, the end of which carries the upward-extending finger t⁵, through the medium of which the ring may be turned, the finger t⁵ projecting through a curved slot w, formed in the cover-plate N². The edge of the slot w is provided with recesses w', in which the finger t⁵ enters laterally under the tension of the spring t⁶ to lock the ring O in its adjusted position. The ring O, however, unlike the corresponding ring in the device of my aforesaid patent, is unprovided with printed marks corresponding with and diametrically opposite to the printing-type thereon, these marks being provided on the covering-plate N² at the notches or recesses w' the better there to be presented to the eye and enable the finger t⁵ to be employed as an index, since whichever of the notches w' it is caused to enter by turning the ring O for the purpose will indicate the legend matter in printing-type in position to be impressed by the stamping operation. The means of adjustment herein described for the outermost ring is desirable, because of the frequent change to which the printing-type is

subjected. In the case of the month and year printing rings the change occurs so seldom as to make special facility for making the change unnecessary.

The minute-printing ring O⁴ is engaged at the teeth t² on its under side through an opening g in the plate N by a ratchet-wheel h on a stud h', carrying a ratchet-wheel h², 75 meshing with an idle ratchet-wheel h³, and which in turn meshes with a ratchet-wheel h⁴ on the minute-shaft p' and corresponding with the wheel h². By these means each movement of the ratchet-wheel o the extent of a tooth moves the ratchet-wheel h and the printing-ring O⁴ to the same extent.

The pawls L and M engage the teeth of the hour-printing ring O³ and the day-printing ring O², respectively, through openings g' and 85 g² in the plate N. The pawl L is pivotally supported on the upper end of a lever f, fulcrumed between its ends on a horizontal rock-shaft f', and extending at its lower end into the path of a rigid trip-finger f² on the adjacent side of the minute-gear o, whereby in each complete revolution of the latter the pawl L is withdrawn, against the tension of its retracting-spring f³, from engagement with one tooth on the hour-printing ring behind 95 the next adjacent tooth thereof, so that when the trip-finger f² clears the lever f the recoil of the spring f³ will cause the pawl L to advance the ring O³.

In order that the ring shall be held in any position to which it is turned, I provide a detent f⁴ on a spring f⁵, fastened to the under side of the plate N and extended into the path of a bent finger f⁶ on the lever f above its fulcrum, which normally bears upward against 105 the detent-spring to force it through the opening g' into the path of the teeth of the ring O³. When, however, the trip-finger f² engages the lever f to turn it, its movement withdraws the finger f⁶ from engagement with the detent-spring f⁵, permitting the recoil of the latter to withdraw the detent from the path of the teeth on the hour-printing ring to allow it to be turned by the subsequent recoil of the pawl, which is resiliently controlled on its 115 pivot by a spring f⁷, extending between it and a projection on the hub of the lever f, and when this recoil occurs it brings the finger f⁶ again to bear against the detent-spring and forces the detent into the path of the teeth of the ring O³ to prevent its turning too far. As a means for avoiding strain on the pawl L and ring O³ by the recoil of the spring f³, I provide a stop f⁸ in position to be engaged by a finger f⁹, extending from the shaft of the lever f to turn with the latter, the stop-finger protruding through an opening in the sleeve surrounding the shaft.

Mechanism similar to that for operating the pawl L is provided for operating the pawl M 130 to actuate the day-printing ring O². This pawl is pivoted on the upper end of a lever e, fulcrumed between its ends on a shaft e' and controlled by a spring e² to actuate by

its recoil the pawl when the lower end of the lever is passed, once in twenty-four hours, by the trip-finger i^3 on the shaft i' . When this occurs, the detent e^3 is withdrawn from the path of the teeth of the day-printing ring O^2 by freeing its controlling-spring e^4 from the bearing contact therewith of the finger e^5 , extending from the lever e at a point above its fulcrum and which ensues from the turning 5 of the lever under the strain of the trip-finger i^3 . When the latter passes the lever e' , the recoil of the spring e^3 retracts it to engage the pawl M , which is resiliently held on its pivot by a spring e^6 with a tooth of the ring O^2 to advance it and return the finger e^5 into bearing contact with the detent-spring to present the detent into the path of the ring-tooth t then engaged by the pawl. 10 15 20 25 30

The printing is performed through an opening j in the plate N^2 . It is effected, as usual, by the impact of a stamp-plate Q , carried by an arm Q' , through the medium of a plunger-rod Q^2 , having a head Q^3 and surrounded by a retracting-spring Q^4 within a socket formed 35 at the end of the arm Q' . Between the plate N^2 and the type-rings the inking-ribbon R extends in position to cross the opening j , being arranged as described in my aforesaid patent or in any other suitable or usual manner. 40

For the purpose of setting the type-printing rings O^2 , O^3 , and O^4 , and particularly the latter, by hand, I provide a lever S , fulcrumed between the ends at x^2 on the bottom of the case A and bifurcated at its inner end, as shown at d , Fig. 8, to embrace the lower attenuated end of the lever C , which when centrally, as it normally is, between the prongs of the bifurcated end of the lever S is movable to oscillate freely under the oscillatory movements of the armature D' . I may provide any suitable means for holding the lever S normally in this position, the particular means shown being a pin c , passed through an opening c^4 in the outer end of the lever into a hole c' in the bottom of the case A , the outer end of the lever being provided centrally with a rigid handle c^2 , by which to work it. When it is desired to stop the running of the clock-movement in the time-stamp case, I lock the armature D' against the poles of the magnet D by turning the lever S at its handle c^2 to bear at its inner bifurcated end against the lever C till an opening c^3 in the outer end of the lever S at the side of the handle c^2 , opposite that at which the opening c^4 is provided, coincides with an opening c^5 in the bottom of the case A , when the pin c is inserted through the opening c^3 into the opening c^5 . By 45 50 55 60 65

releasing the clock motor or spring with the same effect as when the magnet D is successively energized and de-energized. This hand

manipulation of the lever C , through the medium of the lever S , would be resorted to to set, (advance,) say, the minute-hand B' of the time-stamp, and accordingly turn the minute-printing ring, as when the primary clock has for any reason required setting, so that the time-stamp and its primary actuating-clock shall correspond as to time. 75

To advance and thus set in case of necessity the hour-hand B^2 and hour-printing ring O^3 and also the date-ring O^2 by manipulating the lever S would be altogether too tedious for practice. I therefore provide for the purpose 80 squared ends b and b' , respectively, at the outer end of the shaft f' , surrounded by the sleeve b^2 , carrying the trip-lever f , and at the corresponding end of the shaft e' , surrounded by the sleeve b^3 and carrying the lever e . By 85 turning toward the left these shafts f' and e' with a key applied to their squared ends through suitable holes a and a' , provided in the clock-dial B , and advancing the hour-hand B^2 to any next succeeding hour indicated on the 90 dial, the lever f will be tripped to advance the hour-printing ring one tooth without affecting any of the rest of the gear, and turning the shaft e' will trip the lever e to advance the date-printing ring one tooth in the same 95 manner. These operations may be performed while the clock is running, as they do not affect the minute-printing mechanism. 100

From the foregoing description of the mechanism the operation will be understood to be 105 as follows: With the electromagnet D connected in the circuit of the battery E , applied in the manner described to the wheel W on the minute-shaft v of a suitable extraneous primary clock, and with the hands of the secondary clock on the time-stamp set to correspond with the time indicated on the primary clock and the time-printing rings set accordingly, the rotation of the wheel W by the minute-shaft v closes the circuit once in each 110 minute. This energizes the magnet D to attract its armature D' , and thus turn the lever C in the direction to free from one or the other of its stops s or s' the spur s^2 and permit the spring of the secondary clock to turn the shaft 115 m' through one-half a revolution, till it is obstructed by the other stop on the lever C . The de-energization of the magnet by breaking the contact at the wheel W by its continued motion thereupon frees the armature, 120 which is then withdrawn by the recoil of the lever-controlling spring t in retracting the lever C to remove the respective stop from the path of the spur s^2 and permit the shaft m' to complete its revolution, with the effect 125 of turning the ratchet-wheel o and the ratchet-wheel h the extent of one tooth, and consequently the minute-printing ring O' the extent of one tooth. At the end of each hour the step-by-step advancement of the ratchet-wheel o will by the gear connection $l^1 l^2 l^4$ of its shaft p' with the hour-hand B^2 have advanced the latter over an hour-space on the dial B , when the trip-finger f^2 on the shaft p' , 130

the latter having made a complete revolution, will engage the lever f and retract it to engage a tooth on the hour-printing wheel O^3 and advance the latter in the manner hereinbefore described. At the end of twenty-four hours, when the shaft i' has made a complete revolution, the trip-finger i^3 engages the lever e to actuate the pawl M to perform its advancing function on the date-printing ring O^2 in the manner hereinbefore described.

I have shown minute, hour, and date rings moved by the releasing action of the armature D' ; but it is entirely within my invention to increase or decrease the number of rings, in the former case to provide for moving the month-ring as well as the date-ring or to provide for the interposition of a ring moving once in ten minutes and having six figures to represent minute-tens, the minute-ring in such case being smaller and having numbers only from blank to naught, and in the latter case to provide for the omission of mechanism for moving the date ring, which in this case may be adjusted by hand in any suitable manner.

What I claim as new, and desire to secure by Letters Patent, is—

1. In a time-stamp, the combination with the printing rings and a motor-actuated train of gears operatively connected with said rings to bring to the point of stamping the type thereon corresponding with divisions of time, of a spring-controlled oscillatory releasing lever carrying an armature and having a bifurcated end provided with stops s and s' , the shaft m' carrying a pinion m meshing with a toothed-wheel n on a shaft n^2 in said train a spur s^2 on the shaft m' normally engaged at each half-revolution of its shaft by one or the other of said stops to restrain the motor of said train, and an electro-magnet arranged to be included with an extraneous clock in an electric circuit successively closed and opened by the action of said extraneous clock, to oscillate the armature, substantially as described.

2. In a time-stamp, the combination with the printing rings and a motor-actuated train of gears operatively connected with said rings to bring to the point of stamping the type thereon corresponding with divisions of time, of a spring-controlled oscillatory releasing lever normally restraining the motor of said train, and an oscillatory hand-lever extending at one end into the path of said releasing lever to oscillate the latter and produce its releasing function by oscillating the hand-lever, and means for fastening said hand-lever against the releasing lever to lock it, substantially as described.

3. In a time-stamp, the combination with the printing rings and a motor-actuated train of gears operatively connected with said rings to bring to the point of stamping the type thereon corresponding with divisions of time, of a spring-controlled oscillatory releasing lever carrying an armature and normally re-

straining the motor of said train, an electro-magnet arranged to be included with an extraneous clock in an electric circuit successively closed and opened by the action of said extraneous clock, an oscillatory hand-lever bifurcated at its inner end where it embraces the adjacent end of the releasing lever, whereby oscillating said hand-lever actuates the releasing lever to produce its releasing function, and means on the outer end of said hand-lever for fastening it against and locking the releasing-lever, substantially as described.

4. In a time-stamp, the combination with a time-keeping train and horizontal rotary printing rings one within the other and each carrying, at suitable intervals about its printing surface, type indicating divisions of time, said printing rings having teeth on their under sides, of spring-controlled trip-levers on rock-shafts and carrying at their upper ends pivotal pawls engaging said teeth, spurs on shafts of the time-keeping train encountering and tripping said levers periodically to operate the pawls to actuate the rings, springs carrying detents to engage said teeth in opposition to the pawls, and fingers normally bearing against said springs to hold the detents in operative position and movable with the said trip-levers, substantially as described.

5. In a time-stamp, the combination with the case having a cover provided with an aperture through which printing is performed and containing a segmental slot provided at intervals along one side with notches, designating marks on the cover at intervals corresponding with those between said notches, a printing ring O having on part of its surface printing type corresponding with said indicating marks on the cover, and a spring-finger on said ring protruding through said segmental slot to afford means for turning it, to enter said notches and lock the ring in any position to which it is turned, and affording an index-finger, substantially as described.

6. In a time-stamp, in combination with a motor-actuated time-train provided with an oscillatory spring-controlled releasing lever normally restraining the motor, and means for periodically actuating said lever to release the motor to actuate the time-train step by step, a minute printing ring, an hour printing ring and a date printing ring, each having on one face printing type and on the other face teeth, and all being rotary and horizontally disposed one within the other, a ratchet-wheel h engaging the teeth of the minute printing ring and geared to the minute-wheel of the time-train, a trip-finger f^2 on the shaft of said minute-wheel, a rock-shaft f' carrying a spring-controlled trip-lever f extending at one end into the path of said trip-finger and having pivotally supported upon its opposite end a pawl L engaging the teeth of the hour printing ring, a trip-finger i^3 on a shaft i' of said train, and a spring-controlled trip-lever e on a rock-shaft e' and extending at one end into the path of said trip-finger i^3 and carrying at

its opposite end a pivotal pawl M engaging the teeth of the date printing ring, substantially as and for the purpose set forth.

7. In a time-stamp, in combination with a clock in the time-stamp case, an oscillatory spring-controlled releasing lever C normally engaging a spur s^3 in the clock-train to restrain its motor and carrying an armature D', an electro-magnet D arranged to be included with an extraneous clock in an electric circuit successively closed and opened by the action of said extraneous clock to actuate the armature, a minute printing ring, an hour printing ring and a date printing ring each having teeth on its under face, a month printing ring and a legend printing ring, said rings being horizontally disposed one within the other and rotatably supported in the case above the clock-train and each having printing type on its upper surface, a ratchet-wheel h engaging the teeth of the minute printing ring and geared to the minute-wheel of the clock-train, a trip-finger f^2 on the shaft of said minute-wheel, a rock-shaft f' carrying a spring-controlled trip-lever f extending at one end into the path of said trip-finger and having pivotally supported upon its opposite end a pawl L engaging the teeth of the hour printing ring, a trip-finger i^3 on a shaft i' of said train, and a spring-controlled trip-lever e on a rock-shaft e' and extending at one end into the path of said trip-finger i^3 and carrying at its opposite end a pivotal pawl M engaging the teeth of the date printing ring, substantially as and for the purpose set forth.

8. In a time-stamp, in combination with a clock in the time-stamp case, an oscillatory spring-controlled releasing lever C normally engaging a spur s^3 in the clock-train to re-

strain its motor and carrying an armature D', an electro-magnet D arranged to be included with an extraneous clock in an electric circuit successively closed and opened by the action of said extraneous clock to actuate the armature, a minute printing ring, an hour printing ring and a date printing ring each having teeth on its under face, a month printing ring and a legend printing ring, said rings being horizontally disposed one within the other and rotatably supported in the case above the clock-train and each having printing type on its upper surface, a ratchet-wheel h engaging the teeth of the minute printing ring and geared to the minute-wheel of the clock-train, a trip-finger f^2 on the shaft of said minute-wheel, a rock-shaft f' carrying a spring-controlled trip-lever f extending at one end into the path of said trip-finger and having pivotally supported upon its opposite end a pawl L engaging the teeth of the hour printing ring, a spring f^5 carrying a detent f^4 and normally engaged by a finger f^6 movable with said trip-lever, a trip-finger i^3 on a shaft i' of said train, a spring-controlled trip-lever e on a rock-shaft e' and extending at one end into the path of said trip-finger i^3 and carrying at its opposite end a pivotal pawl M engaging the teeth of the date printing ring, and a spring e^4 carrying a detent e^3 and normally engaged by a finger e^5 movable with the trip-lever e , the whole being constructed and arranged to operate substantially as described.

JACOB J. BUSEN BENZ.

In presence of—

M. J. FROST,
J. H. LEE.
